US0D1003910S

(12) **United States Design Patent** (10) **Patent No.:** **US D1,003,910 S**
(45) **Date of Patent:** **** Nov. 7, 2023**

(54) **DISPLAY SCREEN OR PORTION THEREOF
WITH GRAPHICAL USER INTERFACE**

(71) Applicant: **Sonos, Inc.**, Santa Barbara, CA (US)

(72) Inventors: **Brandon Lynne**, Santa Barbara, CA (US); **Ryan Kitson**, Santa Barbara, CA (US)

(73) Assignee: **Sonos, Inc.**, Santa Barbara, CA (US)

(**) Term: **15 Years**

(21) Appl. No.: **29/785,652**

(22) Filed: **May 26, 2021**

Related U.S. Application Data

(63) Continuation of application No. 29/704,424, filed on Sep. 4, 2019, now Pat. No. Des. 922,419.

(51) **LOC (14) Cl.** **14-04**

(57) **CLAIM**

The ornamental design for a display screen or portion thereof with graphical user interface, as shown and described.

DESCRIPTION

The patent or application file contains at least one drawing executed in color. Copies of this patent or patent application publication with color drawing(s) will be provided by the Office upon request and payment of the necessary fee.

The FIGURE is a front view of a display screen or portion thereof with graphical user interface according to our new design.

The broken line showing of a display screen or portion thereof with graphical user interface is included for the purpose of showing portions of the article which form no part of the claimed design.

**1 Claim, 1 Drawing Sheet
(1 of 1 Drawing Sheet(s) Filed in Color)**
